ELECTRIC WEFT DETECTOR

Elbridge R. Holmes, Worcester, Mass., assignor to
 Crompton & Knowles Loom Works, Worcester,
 Mass., a corporation of Massachusetts

Application January 20, 1934, Serial No. 707,559

9 Claims. (Cl. 139—273)

This invention relates to improvements in electrical weft detectors for looms and it is the general object of the invention to provide a detector which exerts a very light pressure on non-indicating detecting beats of the loom but controlled to increase the pressure on indicating beats to insure better contact.

A well-known form of electrical detector employs detector wires or electrodes which project through the front wall of the shuttle to engage the yarn. A sufficient supply of weft keeps the electrodes insulated from each other, but when the supply is exhausted, a metallic ferrule on the bobbin or quill is uncovered and electrically connects the electrodes to close an external circuit the effect of which is to bring about either loom stoppage or weft replenishment. Electrical detectors are usually employed with fine yarn, and the pressure of the detectors against the yarn is reduced to a minimum. It is found in certain instances, however, that a pressure which is sufficiently light for a very fine weft is hardly enough to hold the electrodes against the ferrule tightly enough to insure good contact. It is an important object of my present invention to permit light pressure on the electrodes when the circuit is not completed, but to cause the electrode to exert a greater pressure on the ferrule as soon as any current whatever flows through the electrodes.

In a form of the invention set forth herein-after I employ a magnet to be in a circuit with the electrodes and so arranged as to move a friction device against the sliding electrodes to retard their movement as soon as the circuit is closed. Under these conditions, should the contact at the ferrule be very light, the friction due to the armature will cause a better contact to exist between the electrodes and the ferrule, thereby insuring the flow of sufficient current to energize the loom controlling electromagnetic device.

In another form of the invention a magnetic field is caused to resist movement of a core at initial indication, and the core is connected to the detector electrodes, thereby holding the latter against the ferrule to increase the pressure of contact.

In both forms of my invention, the detector is so controlled and constructed that an initial effort on the part of the detector tending to give an indication will produce a magnetic field which is effective to improve the contact and thereby give a more certain indication.

With these and other objects in view which will

appear as the description proceeds, my invention resides in the combination and arrangement of parts hereinafter described and set forth in the claims.

In the accompanying drawings, wherein a convenient embodiment of my invention is set forth,

Fig. 1 is a side elevation of a part of a loom having the preferred or first form of my invention applied thereto,

Fig. 2 is a top plan view of a part of the structure shown in Fig. 1,

Fig. 3 is a side elevation of the first form of my invention,

Fig. 4 is a front elevation of the structure shown in Fig. 3 looking in the direction of arrow 4, 15 Fig. 3,

Fig. 5 is a diagrammatic view of the circuit for the first form of the invention,

Fig. 6 is a vertical section on line 6—6 of Fig. 4,

Fig. 7 is a view similar to Fig. 3, but showing 20 a modified form of the invention, and

Fig. 8 is a plan view looking in the direction of arrow 8, Fig. 7.

Referring to the drawings, the loom 10 is provided with a lay 11 having a shuttle box 12 with 25 binder 13 and box back 14 between which the boxed shuttle S may be located when the lay is in forward position. The shuttle has a weft compartment 15 and the front wall thereof is provided with a slot 16 which exposes a part of quill 30 or bobbin 17. As shown herein the bobbin is provided with a metallic ferrule 18 which is normally covered by the weft W but which is uncovered when the supply of weft is depleted to a point rendering a change in loom operation necessary. 35 During the normal operation the lay moves the boxed shuttle forwardly while stationary with respect to the lay, thereby permitting weft detecting.

The detector mechanism is of the electrical type 40 and comprises a body 20 of insulating material in which are slidably mounted detector wires or electrodes 21 and 22, each provided with a detecting head 23. Each wire passes through a compartment 24 formed within the body 20 and is 45 surrounded by a light coil spring 25 tending to hold the latter yieldingly in rearward position toward the advancing lay. Each wire passes through a nut or circuit terminal 26 which affords bearing for the front end of the wire and 50 also provides means for electrically connecting the sliding wire with a circuit to be described. The part of the detector already described may be similar to that shown in the Payne Patent No. 1,924,197. 55

In the first or preferred form of my invention, shown in Figs. 1 to 6, a fixed support 30 is secured in any approved manner to the loom and has the body 20 fastened thereto with the electrodes in alignment with the slot 16. The sliding detector wires are extended forwardly as at 35 to lie over a pad 36 of insulating material carried by an armature 37 located to be attracted by the cores 38 of electromagnets 39. The latter are held by a clip 40 which may be welded or in any other way secured to a bracket 41 held to the support 30 by screws 42. As shown in the drawings the body 20 may also be secured to this bracket 41 although the particular manner of mounting the detector proper and the electromagnets is immaterial.

The top 43 of the bracket 41 carries a pair of spaced vertical rods 44 threaded into said top and held in adjusted position by nuts 45. Cotter pins 46, or the like, hold the armature 37 at the desired adjusted position relatively to the electrodes, or wires 21 and 22.

In Fig. 5 I have shown a circuit which is closed by a bare ferrule 18. When the ferrule contacts with the wires 21 and 22 the following circuit will be closed: source of electric power 50, wire 51, sliding electrode 21, ferrule 18, sliding electrode 22, wire 52 the magnets 39 which are connected in series, wire 53 to the ground, and from the ground by way of wire 54 to an electromagnetic loom controller 55, and from thence by wire 56 back to the source of power. Current will flow in this circuit as soon as the electrodes contact with the ferrule, and will energize the magnets 39, whereupon the armature 37 will be raised to the dotted line position shown in Fig. 4 to lift the friction device 36 against the extended ends 35 of the electrodes. Thereafter, forward movement of the electrodes is resisted with resultant increased pressure between the electrodes and the ferrule. In this way assurance is given that even though a light contact is initially established at the ferrule, nevertheless, the remainder of the detecting operation will be improved by increasing the pressure against the ferrule as described.

In the modified form set forth in Figs. 7 and 8 I illustrate an arrangement whereby the circuit is maintained throughout the time that the ferrule has contact with the electrodes. In carrying out this form of my invention I employ the same type of weft detector as that shown in Figs. 3 and 4, with detector wires 21 and 22 to be electrically connected when engaging a bare ferrule 18.

Unlike the first form, however, I provide for yieldingly holding the electrodes rearwardly by a spring 60 which acts between a stand 61 and a lever 62 pivoted as at 63 to a part of the stand. The upper end of the lever has pivoted thereto a pad of insulating material 64 on a carrier 64a which is free to swing in a horizontal plane about a pin 62a on arm 62 and rests on a shoulder 65 also on the lever. The pad 64 engages the forward ends of the detector wires 21 and 22 and transmits the yielding force of spring 60 to said wires, tending to hold them rearwardly. If desired I may incline that face of the pad which engages the wires so that as the lever swings rearwardly around its pivot 63 the wires will be given a slight upward thrust tending always to hold them in good electrical contact with the guides 26. Forward movement of the surface to be detected will push the pad to the right as viewed in Fig. 7 against the action of spring 60, and after the lay passes front center said spring will

push the wires rearwardly, thus holding them against the surface to be detected or the ferrule 18, as the case may be, during rearward motion of the lay.

In order to increase the resistance to the motion of the electrodes when indicating weft exhaustion, I provide a solenoid 70 mounted on the stand 61 and having a core 72 attached by means of a link 73 to the lever 62. Part of the core will normally lie outside the solenoid, as shown in Fig. 7, so that the magnetic field will tend to move the core to the left, as viewed in Fig. 7, or in a direction to hold the electrodes 21 and 22 against the surface being detected. Shoulders 80 on the detector wires limit their rearward motion in both forms of the invention.

The wiring for the solenoid is not specifically set forth herein, but is substantially the same as that shown in Fig. 5, the solenoid replacing the magnets 39. When this circuit is closed at 20 exhaustion of weft, as already described, resultant magnetic field created by the solenoid will attract the core 72, thereby increasing the pressure between the detector wires and the ferrule. Since the core is normally held displaced 25 with respect to the magnetic field by the shoulders 80, it will always tend to establish a better contact at the ferrule whenever current is flowing through the electrodes. It will be noted that, unlike the disclosure of the first form, the wires 30 are not subjected to any opposed force tending to prevent them from following the ferrule when the lay moves rearwardly. In the second form of the invention, therefore, the entire time during which the ferrule could have contact with 35 the detectors can be employed to set the electromagnetic device 55.

From the foregoing it will be seen that I have provided means whereby a weak and insufficient current due to a defective initial contact at the 40 ferrule can be utilized to improve the contact and thereby result in the flow of sufficient current to energize the loom controller 55. It will be seen that this result is accomplished by causing the initial flow of current to produce a magnetic 45 field which is thereby rendered effective to increase the pressure on the electrodes. It will also be seen that in each form of the invention the sliding wires are subjected to an upward force exerted laterally of their length which 50 holds them in close sliding engagement with the guides or terminals 26, thereby further insuring proper contacts throughout the circuit. In this way I not only insure correct contact at the bobbin but also at those fixed points from which 55 the current is tapped off to feed the loom controller 55. When weaving with very fine yarns the feeder pressure can be reduced to a minimum to avoid abrasion of the yarn, but when contact 60 occurs at weft exhaustion, the pressure is automatically increased.

Having thus described my invention it will be seen that changes and modifications may be made therein by those skilled in the art without departing from the spirit and scope of the invention and I do not wish to be limited to the details herein disclosed, but what I claim is:

1. In a weft detector for a loom having a surface to be detected, a sliding electric detector to engage and be moved by the surface, a friction device to have engagement with the detector, and electromagnetic means brought into action by an indication of exhaustion of weft given by the detector and effective to move the friction 75

device against the detector to increase the pressure between the detector and surface.

2. In a loom operating with a weft supply and an electric conducting ferrule which is normally covered by the supply but uncovered when the said supply becomes substantially depleted, a pair of electric contact devices engaging the weft supply with a given normal pressure on detecting non-indicating beats of the loom, electromagnetic means brought into action when the contact devices engage the conducting ferrule, and a friction pad controlled by the electromagnetic means to exert lateral pressure on the contact devices.
- 15 3. In an electric weft detector for looms having a metallic surface to be uncovered as weft exhaustion approaches, a sliding detector to have electric contact with the metallic surface, a circuit terminal through which the detector slides, and electro-magnetic means to be energized by contact of the detector and metallic surface to exert a lateral force on the detector to effect increased contact pressure between the detector and circuit terminal.
- 25 4. In an electric weft detector for a loom operating with an electric conducting surface to be uncovered as weft exhaustion approaches, a supporting body, a metallic detector slideable with respect to the body, a circuit terminal carried by the body to have sliding contact with the detector, and electromagnetically operated means rendered effective by electric contact between the detector and the conducting surface to exert a force on the detector in a direction to move the latter into close contact with the circuit terminal.
- 35 5. In an electric weft detector for a loom operating with an electric conducting surface to be uncovered as weft exhaustion approaches, a sliding electric detector element to engage and be moved by the conducting surface, a circuit terminal element having sliding engagement with the detector element when the latter is moved by the conducting surface, and electro-magnetically operated means rendered effective by electric contact between the detector element and the conducting surface to exert a force tending to cause relative motion of the elements toward each other in a direction lateral with respect to the direction of motion of the detector element to effect close sliding contact between the elements.
- 45 6. In an electric weft detector for looms having a metallic surface to be uncovered as weft exhaustion approaches, a sliding detector element to have electric contact with the metallic surface,

a circuit terminal element with respect to which the detector slides, and electro-magnetic means to be energized by contact of the detector and metallic surface to exert a lateral force on one element tending to move the same toward the other element to effect increased contact pressure between the elements, and to exert a force on the detector element tending to hold the latter firmly against the metallic surface.

7. In an electric weft detector for a loom operating with an electric conducting surface to be uncovered as weft exhaustion approaches, a sliding electric weft detector to have engagement with the conducting surface, a circuit terminal to have sliding engagement with the detector, and electro-magnetically operated means rendered effective by contact between the detector and the conducting surface tending to hold the detector against the detecting surface and also cause relative lateral movement between the detector and the circuit terminal to the end that the electro-magnetically operated means effects close electric contact between the detector and the conducting surface and also between the detector and the circuit terminal.

8. In an electric weft detector for a loom operating with an electric conducting surface to be uncovered as weft exhaustion approaches, an electric weft detector to be moved by the conducting surface, a circuit terminal to have sliding engagement with the detector when the latter is moved by the conducting surface, an electro-magnetic device to be energized by electric contact between the detector and the conducting surface, and means operatively related to the electro-magnetic device and detector tending to resist movement of the latter by the conducting surface and also tending to move the detector laterally into close sliding electrical engagement with the circuit terminal.

9. In an electric weft detector for a loom operating with an electric conducting surface to be uncovered as weft exhaustion approaches, an electric weft detector to be moved by the conducting surface, a circuit terminal to have sliding engagement with the detector when the latter moves, and electro-magnetically operated means tending to resist movement of the detector by the conducting surface and also exert a force tending to produce relative lateral movement between the detector and the circuit terminal in a direction to cause close electric engagement between said detector and circuit terminal.
